(57) **CLAIM**

The ornamental design of a bezel for system storage unit, as shown and described.

DESCRIPTION

FIG. 1 is a front, right perspective view of the bezel;

FIG. 2 is a front, left perspective view of the bezel;

FIG. 3 is a front view of the bezel;

FIG. 4 is a right side view of the bezel;

FIG. 5 is a top view of the bezel; and,

FIG. 6 is a left side view of the bezel.

The bottom view of the bezel is identical to FIG. 5.

The back view of the bezel is unornamented.

The broken lines are shown in the views for illustrative purposes only and form no part of the claimed design.
